AUTOMATIC STARTER CONTROL FOR INTERNAL COMBUSTION ENGINES

Clinton S. Janes, Elmira, N. Y., assignor to
 Eclipse Machine Company, Elmira, N. Y., a
 corporation of New York

Application September 12, 1936, Serial No. 100,567

3 Claims. (Cl. 290—38)

The present invention relates to an automatic starter control for internal combustion engines and more particularly to a starter control embodying special provisions for preventing undesired interruption of the cranking operation.

When starting internal combustion engines in warm weather, it often happens that one or more of the cylinders of the engine will fire spasmodically and then stop firing. If the starter gearing is of the conventional automatically engaging type, this "false start" may disconnect the gearing, and if an automatic starter control is used, the cranking current will be interrupted until the engine and starting motor have come to rest, whereupon the cranking operation will be resumed.

If starter gearing be used which is not disengaged automatically by a false start, it is sometimes preferred to maintain the cranking operation without interruption until a true start is secured, and in that case the automatic starter control used must embody provisions for distinguishing between a false and a true start so as to maintain the starting circuit closed irrespective of false starts.

It is an object of the present invention to provide a novel automatic starter control embodying provisions for maintaining the cranking operation irrespective of abortive explosions or false starts of the engine.

It is another object to provide such a device in which the cranking circuit is automatically interrupted responsive to self-operation of the engine, which is arranged to hold the cranking circuit closed until the engine is consistently self-operative.

It is a further object to provide such a device embodying provisions for interposing a time delay between the inception of self-operation of the engine and the interruption of the cranking circuit, in order to distinguish between a false or abortive start and a true start.

Further objects and advantages will be apparent from the following description taken in connection with the accompanying drawing in which:

Fig. 1 is a semi-diagrammatic illustration of one preferred embodiment of the invention; and

Fig. 2 is a similar view of a second preferred embodiment thereof.

Referring first to Fig. 1 of the drawing, there is illustrated a starting circuit including a battery 1 grounded at 2 and connected by a lead 3 to an automatic controlling device indicated generally at numeral 4. As here illustrated, this de-

vice consists of a magnetic starting switch 5, one contact 6 of which is connected to the battery lead 3 and the other contact 7 is connected by a lead 8 to a binding post 9 which is connected by a lead 11 to a starting motor SM which is grounded at 12 to complete the starting circuit. It will be understood that the starting motor SM is connected by any suitable form of automatically engaging and disengaging starter drive to an engine to be started, which structure is not illustrated since it forms no part of the present invention.

According to the present invention, a control circuit is provided for the magnetic starting switch 5 including a manual switch 13 which is preferably the ignition switch of the engine, and is connected by a lead 14 to the battery lead 3 and by a lead 15 to the solenoid 16 of the magnetic starting switch. The solenoid 16 is connected by a lead 17 to a pair of contacts 18, 19, the contact 18 being mounted on a fixed bracket 21, and contact 19 being mounted on a spring arm 22 anchored and grounded at 23 and provided with a pendulously supported weight 24 at its free end.

Means for controlling the contacts 18, 19 is provided in the form of an electromagnetic structure comprising a coil 25 and an armature 26, which armature is arranged to move a bellcrank lever 27 about a fixed pivot 28 and thereby cause the free end 29 of the lever to engage the weight member 24 on the spring arm 22 and move it backward so as to disengage contact 19 from contact 18. The armature 26 is normally maintained in extended position by suitable means such as a spring 31.

Coil 25 is arranged to be energized from the cranking circuit, and for that purpose is included in a branch circuit including a lead 32 connected to the contact 7 of the starting switch, contacts 33 and 34 which are normally maintained closed by an adjustable spring device 35, lead 36 and ground lead 37. Means are provided for preventing the energization of coil 25 during the cranking operation in the form of an electromagnetic controlling device for contacts 33, 34 comprising a magnet 38 energized by a single turn 39 of the starting circuit lead 8. The magnet 38 is provided with an armature 41 carrying contact 33, and is arranged to attract said armature and open contacts 33, 34 during heavy current flow through the cranking circuit, but to release said armature and permit the spring device 35 to close said contacts when the current in the starting circuit is reduced by the release 55

of the cranking load thereon when the engine starts. An adjustment such as indicated at 42 is preferably provided for determining the minimum gap between the armature 26 and magnet 38 so as to regulate the amount of current flow necessary to retain the armature in its attracted position.

According to the present invention, means are provided for preventing the opening of the control contacts 18, 19 for a predetermined time after the cranking current is reduced due to the initial explosions of the engine. As above set forth, this time delay is provided for the purpose of distinguishing between a false start and a true start, 10 and to maintain the energization of the starting circuit until a true start is secured. As here shown, this means is in the form of a dash pot indicated generally at numeral 43 comprising a cylinder 44 and a piston 45 slidably therein and 20 connected by a stem 46 to the armature 26 of the control relay.

A restricted inlet passage 47 into the cylinder 44 is provided for admitting air above the piston 45 and thereby permitting it to move downward, 25 and adjusting means for such inlet is preferably provided as indicated at 48.

Since it is desirable to permit the armature 26 to return quickly to its idle position when the coil 25 is deenergized in order to set the flexible strip 22 in vibration, a check valve 49 may be provided for permitting rapid egress of the air trapped above the piston 45. This function may also be satisfactorily performed by forming the piston 45 with a flexible cup-shaped obturator as 35 indicated at 51.

Means are provided for maintaining the energization of the control relay in order to hold contacts 18, 19 open during self-operation of the engine. As here illustrated, this lock-out means 40 is in the form of a coil 52 energized from an engine-driven generator G by means of a lead 53 and grounded by means of a lead 54 to complete the lock-out circuit.

In the operation of this embodiment of the invention, starting with the parts in idle position as illustrated, closure of ignition switch 13 causes energization of solenoid 16 and consequent closure of the magnetic starting switch 5 whereby cranking of the engine is initiated. The coil 25 of the control relay is momentarily energized by closure of the starting switch 5, but before any substantial movement of the armature 26 thereof can take place, the heavy flow of current through the single turn coil 38 of the cranking circuit opens contacts 33, 34 and deenergizes coil 25.

When the engine fires, the release of the cranking load on the starting circuit weakens the current flowing therethrough so that the magnet 38 is weakened and permits contacts 33, 34 to close. Armature 26 of the control relay thereupon begins to move downward in a direction to open the contacts 18, 19, but such motion is delayed by the dash pot 43 so that if the initial explosions of the engine are abortive and the engine does not continue self-operative, the starting motor will pick up the engine and resume cranking, and the heavy cranking current through the single turn coil 38 will cause the magnet 38 to open contacts 33, 34, thus deenergizing the relay coil 25, whereupon armature 26 is returned to its idle position by spring 31.

When the engine becomes continuously self-operative so that the load on the cranking circuit 75 remains at a low value for a predetermined length

of time sufficient to distinguish between a false start and a true start, the armature 26 of the control relay moves downwardly, opening contacts 18, 19 and thereby deenergizing the magnetic starting switch 5 and opening the starting circuit. Coil 25 of the control relay is thus cut off from the battery 1, but is not completely deenergized since a slight amount of current continues to traverse the coil due to the rotation of the starting motor armature in its residual field. Ample time 10 is thus provided for the generator G to energize the lock-out coil 52 and retain armature 26 in attracted position as long as the engine is self-operative.

In case of engine stall, the lock-out coil 52 is 13 deenergized, whereupon armature 26 is released and snaps back to its normal position, setting the flexible strip 22 in vibration whereby contacts 18, 19 are prevented from effective closure for a time interval sufficient to enable the engine to come 20 completely to rest and prevent engagement of the starting mechanism during a back-rock of the engine.

In the embodiment of the invention illustrated in Fig. 2, the elements of the starting circuit are 23 the same as in the embodiment first described, and the elements of the control device are also similar except for the features of the control relay. As here illustrated, the control relay 55 is provided with a clapper type armature 56 pivoted 30 at 57 and arranged to operate a contact arm 58 by means of a "snap action" in the form of an elastic toggle lost motion connection 59. Contact arm 58 is pivoted and grounded at 61 and carries movable contact 62 corresponding to contact 35 18 in the previous embodiment.

Armature 56 is connected by means of a universal link 63 with one end of a flexible bellows 64, the opposite end of which is carried by an adjustably mounted support 65. A restricted opening 66 is provided for the bellows, and an adjustable valve member 67 is provided for controlling the rate of flow of air through said opening.

The operation of this embodiment of the invention is similar to that previously described 45 except that the bellows 64 forms a unitary retarding means for the armature 56 in both directions so that in view of the elastic toggle connection between the armature 56 and the contact arm 58, a time delay is provided both for opening and 50 for closing the contacts 18, 62. It will be readily appreciated that the duration of the two time delays may be independently varied by adjustment of the support 65 to vary the tension of the bellows 64, whereby it is possible to insure that the 55 time delay between the energization of the relay coil 25 and the opening of contacts 18, 62 may always be sufficient to properly distinguish between a false and a true start, and the time interval between the deenergization of the control 60 relay and the closure of contacts 18, 62 may always be sufficient to allow the engine to come completely to rest.

Although but two embodiments of the invention have been shown and described, it will be 65 understood that other embodiments are possible and that various changes may be made in the forms and arrangements of the parts without departing from the spirit of the invention as defined in the claims appended hereto.

What is claimed is:

1. In an automatic starter control, a starting circuit including a magnetic starting switch, a control circuit for closing said starting switch, means including a solenoid in series in the start- 75

ing circuit for energizing said control circuit to initiate cranking of the engine and for deenergizing said control circuit responsive to self-operation of the engine, and means for delaying for predetermined times both the energization and deenergization of the control circuit.

2. In an automatic starter control, a starting circuit including a magnetic starting switch, a control circuit for closing said starting switch, means including a solenoid in series in the starting circuit for energizing said control circuit in case of engine stall and for deenergizing the control circuit when the engine becomes self-operative, and unitary means for delaying the energization of the control circuit for a predetermined time after the engine comes substantially to rest, and for delaying the deenergization of the control

circuit for a predetermined time after the engine becomes self-operative.

3. In an automatic starter control, a starting circuit including a magnetic starting switch, a control circuit therefor including a pair of contacts, an electromagnet energized from the starting circuit, an armature movable thereby, a yielding lost motion connection between the armature and said contacts for opening the contacts, means for retarding the motion of the armature to delay opening the contacts for a predetermined time after energization of the electromagnet, and means for delaying effective closure of the contacts for a predetermined time after release of the armature.
